(57) **CLAIM**

The ornamental design for an exercise mat, as shown and described.

DESCRIPTION

This application claims the benefit of priority to U.S. patent application Ser. No. 12/404,576, filed Mar. 16, 2009, which is incorporated herein by reference in its entirety.

FIG. 1 is a top plan view of a first embodiment of the exercise mat, showing my new design;

FIG. 2 is a front elevation view of the first embodiment thereof, the back elevation being the same;

FIG. 3 is a left elevation view of the first embodiment thereof, the right elevation being the same;

FIG. 4 is a bottom plan view of the first embodiment thereof;

FIG. 5 is a top perspective view of the first embodiment thereof;

FIG. 6 is a bottom perspective view of the first embodiment thereof;

FIG. 7 is a top plan view of a second embodiment;

FIG. 8 is a front elevation view of the second embodiment thereof, the back elevation being the same;

FIG. 9 is a left elevation view of the second embodiment thereof, the right elevation being the same;

FIG. 10 is a bottom plan view of the second embodiment thereof;

FIG. 11 is a top perspective view of the second embodiment thereof;

FIG. 12 is a bottom perspective view of the second embodiment thereof;

FIG. 13 is a top plan view of the third embodiment;

FIG. 14 is a front elevation view of the third embodiment thereof, the back elevation being the same;

FIG. 15 is a left elevation view of the third embodiment thereof, the right elevation being the same;

FIG. 16 is a bottom plan view of the third embodiment thereof;

FIG. 17 is a top perspective view of the third embodiment thereof;

FIG. 18 is a bottom perspective view of the third embodiment thereof;

FIG. 19 is a top plan view of the fourth embodiment;

FIG. 20 is a front elevation view of the fourth embodiment thereof, the back elevation being the same;

FIG. 21 is a left elevation view of the fourth embodiment thereof, the right elevation being the same;

FIG. 22 is a bottom plan view of the fourth embodiment thereof;

FIG. 23 is a top perspective view of the fourth embodiment thereof; and,

FIG. 24 is a bottom perspective view of the fourth embodiment thereof.

The broken lines in FIGS. 7-12 represent stitching and form a part of the ornamental design.

The broken lines in FIGS. 19-24 represent environmental features and form no part of the ornamental design.
